UNITED STATES PATENT OFFICE.

HENRY L. NARAMORE, OF SHARON, MASSACHUSETTS.

BEVEL.

SPECIFICATION forming part of Letters Patent No. 371,210, dated October 11, 1887.

Application filed June 17, 1887. Serial No. 241,615. (No model.)

To all whom it may concern:

Be it known that I, HENRY L. NARAMORE, of Sharon, in the county of Norfolk and State of Massachusetts, have invented certain new and useful Improvements in Mechanics' Rules or Gages, of which the following is a specification.

My invention has for its object to provide an improved gage or rule for cabinet-makers, carpenters, joiners, and other mechanics, whereby the dimensions and angles or form of a thing may be readily ascertained—as, for example, where it is desired to ascertain the length and angles of the sides and ends of a board to be fitted in a frame-work or casing or between two walls or points.

It not infrequently happens that carpenters, cabinet-makers, and others are in the prosecution of their work required to fit boards in casings or between walls, partitions, or the like, where the angles of the ends of the board to be cut differ from each other, or are other than a right angle to the edge of the board, or both. This necessity arises, for instance, quite often in the building of a staircase. Various expedients are resorted to for obtaining the dimensions and form of a board to be fitted in such place, all of which consume a considerable amount of time and are attended with more or less perplexity to the workman, and unless the utmost care is exercised inaccuracy will result.

My invention consists in an extensible bar or rod provided on each end with an adjustable arm gage or rule, each of which arms may be adjusted to any angle with respect to the bar or rod, whereby the length of a board and the angles of the sides or walls of the casing or the like to which it is to be fitted may be quickly and accurately ascertained.

Reference is to be had to the accompanying drawings, and to the letters of reference marked thereon, forming a part of this specification, the same letters indicating the same parts wherever they occur, of which drawings—

Figure 1 represents a perspective view of the invention in opened position. Fig. 2 represents a longitudinal vertical section of the invention in closed position, the section being taken on the line $\alpha\alpha$, Fig. 3. Fig. 3 represents a bottom plan view of the invention in closed position.

In the drawings, A represents an extensible bar or rod, to each end of which an arm, C, is adjustably secured, as shown. As hereshown, 55 bar A is constructed of two rectangular parts, $a\ a'$, adapted to slide upon each other. Part a is provided on its inner end with a stud, b, which extends down through a slot, c, in part a' , to the lower end of which stud is affixed a 60 block, d, adapted to slide in a shallow groove, e, formed in the bottom of part a' . It is obvious that block d might constitute an integral part of stud b—that is, be formed as a kind of head to said stud—the upper end of which is 65 screw-threaded to receive a thumb-nut, f. To the inner end of part a' is secured a stud, g, which extends upward through a slot, h, in part a , and is provided on its upper end with a thumb-nut, i, as shown. By loosening the 70 thumb-nuts the bar may be extended or shortened within limits permitted by its construction, and when moved to desired position it may be secured in such position by turning down the thumb-nuts f i. Again, it is obvious 75 that either of the studs b g may be provided on its upper end with a simple head, the other having a thumb-nut, as shown, one such thumb-nut being sufficient to secure the parts in adjusted position.

Each arm C is provided with a slot, j, to receive the shank of a bolt or stud, k, in the outer end of each part $a\ a'$, by means of which each of said arms may be moved to any position on its respective part within the limits of slot j, 85 adjusted at any angle with respect to the bar, and fixed or held in such adjusted position by means of the thumb-nut l on the upper end of stud k.

It is obvious that the bar A and arms C may 90 be marked off in inches and fractions thereof, and in some instances I have constructed the device in this way.

The arms C are preferably of such form that they may be folded under the bar, as represented in Figs. 2 and 3, so the device, when in closed position, will constitute a bar of rectangular form, convenient for transportation and packing.

Having thus explained the nature of my invention, what I claim is—

A tool or gage for wood-workers and other mechanics, consisting of an extensible rod or bar, A, consisting of the two parts $a\ a'$, the

former provided with a slot, *h*, and the latter with the slot *c* and shallow groove *e*, a thumb-screw, *f*, on the inner end of part *a*, having its shank extended through slot *c* in part *a'*, a 5 block, *d*, affixed to the end of said screw and adapted to slide in groove *e*, and thumb-screw *i* on the inner end of part *a'*, having its shank extended through slot *h* in part *a*, said rod or 10 bar *A* being provided on its ends with adjustable arms *C*, substantially as and for the purposes set forth.

In testimony whereof I have signed my name to this specification, in the presence of two subscribing witnesses, this 13th day of June, A. D. 1887.

HENRY L. NARAMORE.

Witnesses:

ARTHUR W. CROSSLEY,
C. F. BROWN.
